PORTABLE CLAMP LOCK

Tryggve Bob Stue, Oslo, Norway

Application March 26, 1946, Serial No. 657,126
In Sweden May 24, 1944

4 Claims. (Cl. 70—19)

1
The invention relates to a portable clamp lock which may be moved from one place to another and be applied at the place where it is to be used. The lock according to the invention may, however, occasionally be mounted in a stationary position.

The lock according to the invention is of the type which is provided with an extended locking element, for instance, in the shape of a bar member or a steel band, which locking element may be pushed or pulled through a guide in the lock casing. The locking element is provided with notches, holes or the like, which cooperate with a latch member in such a manner that the locking element, when the lock is locked, can be moved in one direction only.

The primary object of the invention is to produce a lock which is adaptable for use within a larger range than the known locks of the said type.

To this end and according to an important feature of the invention the locking element is mounted turnably about its longitudinal axis and provided with a plurality of closely spaced grooves, each extending around the circumference of the element. As a result, it is possible during the locking to turn the locking element into the position best suited for the object which is to be locked. This is especially of importance when the locking element at its one end is provided with a hoop or hook shaped portion, intended to be brought into engagement with one of the two objects which are to be locked together. The two objects here referred to may for instance, consist of a stationary object, such as a railing, an iron hook fastened to a house wall, a container or the like, while the other object may be a bicycle, a chair-sled, a perambulator or the like. The objects may, however, also be two loose objects, for instance, a pair of skis or two wheels of a carriage. It is further possible that the object after having been locked may be turned around, which is at times desirable.

The possibilities of using the lock may be further increased according to another feature of the invention by providing the lock casing with two or more guides for two or more locking elements.

According to a further important feature of the invention, the locking element is constructed in the form of a chain.

The invention comprises also lock mechanisms which are especially suited for the locking elements employed according to the invention.

Further features and advantages of the in-

2
vention will appear from the following description with reference to the drawings. These serve to illustrate some embodiments of the invention which, however, is not limited to these special embodiments but comprises everything covered by the claims.

In the drawing:

Fig. 1 is a perspective view of an embodiment of a lock according to the invention.

10 Fig. 2 is a longitudinal section on the line II—II in Fig. 1.

Figs. 3 and 4 are sections on the line III—III in Fig. 2, with the latch member in two different positions.

15 Fig. 5 is a section to a larger scale on the line V—V in Fig. 2.

Fig. 6 is an elevational detail view.

Fig. 7 is a section on the line VII—VII in Fig. 8, of another embodiment of the lock mechanism.

20 Fig. 8 is a section on the line VIII—VIII in Fig. 7.

Fig. 9 is a vertical section of another embodiment of a lock according to the invention.

Fig. 10 is a plan view to Fig. 9.

25 Fig. 11 is a top plan detail of a plate in the lock casing; and

Fig. 12 is a top plan detail of a spring control lever in the lock casing.

The lock shown in Figs. 1—6 comprises a lock casing 1, which in plan view has approximately the shape of an I. The lock casing is provided with four through-going bores or guides 2, 3, 4, 5, for extended locking elements. In Fig. 1 two such locking elements 6 and 9 are shown. The locking element 6, which is placed in the guide 4 is at its one end provided with a hook-shaped hoop 7, intended to be hooked around an object or a portion of an object which is to be locked fast.

30 The straight portion of the locking element is provided with slots or grooves 8, which extend along the circumference and are equally spaced.

The locking member 9 is in a similar way provided with a hook-shaped portion 10, which at its free end is provided with an axial bore 11. The straight portion of the locking element is in a similar way as the element 6 provided with slots or grooves 12.

The lock is further provided with a cylinder 50 lock mechanism. This comprises a cylinder 13 of a known construction which cooperates with tumblers 14. A spring influenced pin 15 which engages in a circumferential groove in the cylinder prevents the same from being displaced in an axial direction. At the end of the cylinder

there is a member 16 which is integral with or rigidly connected with the cylinder 13. The member 16 carries a laterally projecting nose 17 which in the locked position of the lock engages in one of the grooves 12 on the locking element 9 and thereby prevents any axial displacement of the latter (see Fig. 3). 18 designates a member which is mounted turnably in a recess in the member 16 and is provided with an outwardly projecting nose 19. In the locked position of the lock as shown in Fig. 3 the member 18 is held by a spring 20 in such a position that the nose 19 engages with one of the grooves 8 on the locking element 6. The recess in the member 16 is, however, formed in such a manner that the member 18 against the influence of the spring 20 may be turned downwards a certain angle from the position shown in Fig. 3, so that the locking element 6 may be pushed downwards, but not be pulled up again.

The tumblers 14 prevent in the usual manner unintended turning of the cylinder 13. By means of a key, which when inserted causes raising of the tumblers, the cylinder may be turned to the position shown in Fig. 4. In this position none of the noses 17 and 19 projects into the guides 4 and 5, and the locking elements 6 and 9, which are not shown in Fig. 4, may in this position of the cylinder be moved freely up and down.

The operation of the lock according to the embodiment described is as follows:

While the cylinder is in the position shown in Fig. 4, the locking elements 6 and 9 are pulled so far apart that the hooks 7 and 10 may be hooked around two parts which are to be locked together. It is here of great advantage that the locking elements according to the invention are freely turnable, so that the hoops 7 and 10 may assume the desired angular position relative to each other best suited to the parts which are to be locked together.

The cylinder is now turned back into locking position and the key is removed. The locking element 9 is now prevented from axial displacement but may still be turned freely. The locking element 6 may be pushed in (down in Figs. 1 and 3), the nose 19 thereby being forced downwards against the influence of the spring 20. When the parts which are to be locked together are tightened against each other they cannot be released from each other except by means of the key belonging to the cylinder lock. The locking element 6 cannot be pulled up because the member 18 cannot be swung further back than to the position shown in Fig. 3.

The different possibilities for using the lock are further to be described in detail in the following.

In the embodiment shown in Figs. 1-6 there are in addition to the guides 4 and 5 two other through-going guides 2 and 3. These are especially intended for use in the case where instead of bar shaped locking elements 6 and 9, locking elements in the form of link chains are to be used, as will be described hereinafter. Such a link chain may then be passed alternately around an object which is to be locked fast and one of the guides in the lock.

In Figs. 7 and 8 there is shown a somewhat modified embodiment of a cylinder lock mechanism applied to a lock according to the invention. In these figures 50 designates the lock casing, 51 a through-going bore in the same, and 52 the cylinder in a cylinder lock of otherwise ordinary construction. Between the cylinder 52 and the bore 51 is located a bore 53. In the latter a pin 75 the other hand, the lever 37 may be swung up-

member 54 is mounted, which with its one end may project into the bore 51 and enter into engagement with a locking element located in the same (which is not shown in the drawing). The pin 54 is sought to be held in engagement with the locking element by means of a helical spring 55, which at its other end bears against a pin 56 which in turn bears against the cylinder 52. In the latter a recess 57 is provided, into which the pin 56 may be pressed when the cylinder 52, from the position shown in Fig. 7, is turned 90° in counter-clockwise direction. When the pin 56 is at the bottom of the recess 57 the pin 54 may be pushed back against the influence of the spring 55, so as to permit of displacement of the locking element situated in the bore 51.

When the lock is in locked position, as shown in Fig. 7, the pin 54 can not be pushed back and the locking element is locked fast.

The lock shown in Figs. 7 and 8 is provided with two through-going bores for locking elements, and the cylinder 52 is therefore in addition to the recess 57 provided with another recess 58 which acts in the same way. 59 and 60 are holes for the free end of the locking hoop.

As will be realized the lock may be constructed appreciably simpler than shown in Figs. 1-6. Firstly the guides 2 and 3 may be dispensed with. Secondly, instead of a turnable and displaceable hoop 10 one may use a hoop, hook, screw or the like which is fixedly or eventually turnably connected with the lock casing.

A few simpler embodiments of a lock according to the invention are shown in the following figures.

In Figs. 9, 10 and 11 there is shown an embodiment of a lock according to the invention with only two through-going guides. In this embodiment a lock mechanism of the ordinary type for padlocks is used instead of a cylinder lock. In these figures 30 designates a lock casing provided with two parallel through-going bores 31 and 32. 33 is an extended locking element in the form of a ball chain. This chain is at its one end provided with a head 34 in the shape of a ring, ball or the like, with larger diameter than the bore 32. At its other end the chain is provided with a needle shaped pin 35 which serves to facilitate the passing of the chain through the bores. Between each ball slots or grooves 36 are formed similar to the slots 8 and 12 in the locking elements 6 and 9.

37 designates a lever which is turnably mounted on a pin 38 provided in the lock casing. A spring 39 tends to turn the lever 37 to the position indicated by dotted lines in Fig. 9. The other end 40 of the spring is passed through a hole 41 in a bar or plate 42, which is displaceably mounted in the lock casing. In the position shown in Fig. 9 the lever 37 as well as the bar 42 are in engagement with the link chain. The bar 42 is hereby mounted in such a way that it can neither be moved upwards nor downwards, so that the locking element mounted in the bore 32 is completely prevented from axial displacement. The lever 37 may, however, be turned upwards against the influence of the spring 39.

A latch member 43 which constitutes a part of an ordinary lock mechanism prevents, in the position shown in Fig. 9, return displacement of the bar 42. At the same time the upper end of the member 43 prevents that the lever 37 may be turned downwards so as to be disengaged from the locking element situated in the bore 31. On

wards against the influence of the spring 39.

The operation of the lock according to this embodiment is as follows:

Return movement of the latch member 43 to the position shown in dotted lines is caused by means of a key. The lock chain 33 is now free and may be pulled out of the bores 31 and 32. This is of importance in case it is desired to exchange the lock chain with another lock chain which is longer or shorter, or with a bar shaped locking element, for instance, similar to those shown in Fig. 1 or Fig. 4.

It is, however, assumed that the lock chain shown in Fig. 9 is to be used. In such case the same is only pulled out of the bore 31 and is thereupon placed around the object or objects which are to be locked. Thereupon the point 35 is inserted through the bore, the latch member 43 is moved by means of a key to the position shown in full lines in Fig. 7, and the lock chain is tightened. This is permitted by swinging the lever 37 upwards against the influence of the spring 39. In any position corresponding to the adjusted tightening, the chain is however locked fast so that it can not be pulled back, because the latch member 43 prevents the lever 37 from being pulled downwards below the position shown in full lines in Fig. 7.

It is believed in view of the foregoing description that a further detailed description of the operation of the invention is unnecessary.

Likewise it is believed that the advantages of the invention will be readily apparent.

Having thus fully described the invention what is claimed and desired to be secured by Letters Patent is:

1. Lock comprising a casing with two bores extending therethrough, a first lock element extending into one of said bores and being longitudinally slidable and rotatable therein, a second lock element extending into the other of said bores and being longitudinally slidable therein, said first lock element having a number of narrowly spaced grooves each extending around the entire circumference thereof, and a locking mechanism within the casing including two latches and a key controlled latch operating member common to both latches, one of said latches being engage-

able in the spaced grooves and operable to lock the first lock element against movement in one direction and being yieldably mounted to accommodate movement of the first lock element in the opposite direction, and the other latch being operative to lock the second lock element against longitudinal movement in either direction.

2. Lock comprising a casing with two bores extending therethrough, a first lock element extending into one of said bores and being rotatable and axially displaceable therein, a second lock element extending into the other of said bores and being rotatable and axially displaceable therein, both of said lock elements being adapted to be locked in adjusted axial position, a single locking mechanism including two latches operable by a single key to lock and unlock said lock elements, one of said latches being a one way acting snap-latch, the other being a two way acting retaining latch.
3. Lock as claimed in claim 2 wherein said locking mechanism includes a cylinder and a spring, the snap-latch being adapted to be turned a certain angle about the axis of the cylinder against the action of said spring, so as to accommodate movement of the related lock element in one direction but not in the opposite direction.
4. Lock as claimed in claim 2 wherein said locking mechanism includes a longitudinally shiftable member adapted to lock said latches simultaneously in operative position.

TRYGGVE BOB STUE.
